UNITED STATES PATENT OFFICE.

JOHN JORGENSON, OF SAN FRANCISCO, CALIFORNIA.

LOCK.

No. 823,174.

Specification of Letters Patent.

Patented June 12, 1906.

Application filed June 7, 1905. Serial No. 284,098.

To all whom it may concern:

Be it known that I, JOHN JORGENSON, a citizen of the United States, residing in the city and county of San Francisco and State of California, have invented new and useful Improvements in Locks, of which the following is a specification.

My invention relates to locks for the doors of residences and other buildings and for vaults and safes and for use generally wherever a lock is desired which cannot be opened except by some one possessing the necessary and exact unlocking instrument.

The object of the present invention is to provide a simple practical absolutely safe lock of the cylinder-knob variety which shall be comparatively cheap to manufacture and which can be easily and instantly adjusted to operate with or without a key or set so it cannot be operated at all.

The invention consists of the parts and the construction and combination of parts, as hereinafter more fully described and claimed, having reference to the accompanying drawings, in which—

Figure 1 is a horizontal section of my lock. Fig. 2 is a section on the line Y Y of Fig. 1. Fig. 3 is a section on the line X X of Fig. 1. Figs. 4 and 5 are perspective views of the component parts of the housing. Fig. 6 is a perspective view of the tumbler-plate. Fig. 7 is a view of the key. Fig. 8 is a longitudinal section of the housing. Fig. 9 is a section on the line O O of Fig. 1.

A and B represent respective inner and outer door-knobs, the outer one made hollow and integral with its hollow knob-shank and integral with its flange 2, which latter is secured to the outside of the door by means of the screws 3, which pass from the inside through the plate 4 and the door. The inner knob B is made integral with its knob-shank, and the latter has a limited reciprocating movement in the plate 4 and is also capable under certain circumstances of a rotative movement in said plate. A spring-pressed dog 5, carried by the inside knob-shank, is adapted to engage suitable notches or recesses in the bore of the plate to hold the knob B from turning for the purpose to be hereinafter described.

The part 6, by which the locking-bolt 7 is retracted, I prefer to term the "latch member" or "actuator," and I shall so designate it hereinafter. This actuator takes the place of the roll-back of most locks and is designed

to operate the bolt 7 by a sliding movement at right angles to bolt 7 rather than by any rotative movement of the actuator or of either of the knobs, although the inner knob 6 is adapted to be turned a quarter-turn or so at a time by depressing dog 5 to permit the actuator to operate or to limit or entirely prevent its actuation, as will be shown later. The bolt 7 is slideable and guided in a suitable sleeve 7'.

The actuator 6 is secured fast at one end to the shank of the inner knob B and in the same plane with the dog 5, and the portion of member 6 proximate to this shank is made 70 slightly wider than the shank and larger than the bore in plate 4 to form abutments 6' to engage against the side of the plate next to the door to prevent the reciprocation of knob B or the actuator except when this wider 75 part of the actuator is brought into alignment with the diametrically-opposed notches 8 9 in the plate 4, and in which notches the dog 5 is engageable. There is a third and shallower notch 11 located between the 80 notches 8 9 for the dog to catch in; but this notch is not sufficiently deep to let the actuator slide through plate 4. Between plate 4 and flange 2 the member 6 has a reduced portion 12, passing through and of such size and character as to be turnable in the slot 13 in bolt 7. A spring 14 keeps the latter normally projected outward to engage the keeper 15 on the door-jamb. This keeper 15 is preferred 85 for its compact and neat appearance and 90 simple construction. It comprises, essentially, a flanged socket-piece adapted to be set in flush with the surface of the jamb, secured in place simply by a screw 16, passed through a hole in the bottom of the socket 95 and having a lateral extension or tongue 17 to lead the tapered end of the bolt 7 properly into the retaining-recess in the socket.

The actuator has two diametrically-opposed convergent cam-surfaces 18, connecting with the portion 12 on the side of the latter adjacent to the outer knob. The spring 14 always tends to press the rear wall of slot 13 (here shown as a pin 19) against the part 12 or 18 of the actuator. The outer end of 100 the member 6 is so mounted in the outer knob-shank as to permit said member when the cams 18 are brought into the same plane with slot 13 to be reciprocated toward the inner side of the door to cause one or the 105 other of these cams to engage the rear wall of slot 13 and retract the bolt 7. The end of

the actuator corresponding to the outer knob is bifurcated to provide a narrow keyway 20 at the outer end, and the ends of the forks operate above and below respective knife-edged projections 23 24 on the interior of the combined hollow housing and carrier 25, in which a part of the actuator 6 is slideable, and which housing and carrier is capable under some conditions of a reciprocating and rotative movement in the outer knob and knob-shank. Figs. 4 and 5 show the respective upper and lower components 25^a 25^b of the housing 25. The housed portion of member 6 has two oppositely-extending lateral projections 26, 15 forming a cross-head which operates in slots 27 in the sides of the housing 25. A spring 28, surrounding the housing, bears against this cross-head and against a ring 29, which is set into and secured to the inside of flange 2, and 20 which spring acts to retract the member 6 normally outward to free the cams 18 of any engagement with the bolt 7. The outer end of the housing 25 is closed except for a thin slot 30, registering with the keyway 20 and 25 adapted to receive a thin instrument, as the key 31.

When the inside knob, to which the actuator is fixed, is turned to bring the actuator into register with the notches 8 9, the dog 5 30 being engaged in one or the other of these notches, the inner knob and actuator are held against further rotation, but both may be moved to retract bolt 7, first, by pushing the key, passing through the slot 30 into the keyway 20, or, second, by taking hold of knob B and pulling on it, or, thirdly, provided a projection 32 on the housing 25 is in register with a slot 33 in ring 29, by pushing in on the exposed end of the housing 25, which pushing 35 action carries both the housing and actuator forward. Any one of these three operations will cause a cam 18 to operate on bolt 7 to retract the latter. It is understood that notches 8 9 lie not only in the same plane with the actuator, but with slot 13 in bolt 7, so that when the actuator is in line with notches 8 9 the actuator may reciprocate to allow a cam 18 to 40 operate, as described. If it is desired, however, to lock the bolt 7 and the actuator 45 against movement, the dog 5 is depressed and the knob B turned a quarter-turn in the right direction to bring the dog into the single shallow notch 11. Then it is impossible to turn either the knob or the actuator or to 50 reciprocate the latter, since the dog prevents rotation and the shoulders 6' of the actuator engage plate 4, and also the cams 18 are brought crosswise of slot 13 and engaged in notch 34 on the slotted part of bolt 7.

55 The notches 8 9 11 coöperate to produce each a separate and different result and are disposed in a definite relation to the projection 32 on the housing 25 and the slot 33 in ring 29. When the dog is in line with notch 8, for example, the projection 32 is also in

line with slot 33, and at that time and only then can the housing be moved in to open the door from the outside without a key. In all other positions of the actuator and knob B in their rotation the projection 32 and slot 33 70 are out of line, and the housing cannot reciprocate because of the stop provided to the projection 32 by the ring-guide 29. When the dog 5 is in line with notch 9, the actuator may be pushed in by means of a key or other 75 suitable instrument inserted into the keyway 20 or by pulling on knob B; but when the dog is in notch 11 everything is locked against either rotative or reciprocal movement. The distance to which the actuator may be pulled 80 or pushed inwardly is limited by suitable means, as the shoulders 7^a.

In order to guard against the lock being picked and to provide for a wide range of action in the construction of the locks, I prefer 85 to employ a tumbler-plate 35, disposed in a recess in the housing 25 and having projecting ends 36 slideable and guided in suitable cam-slots 37 in the walls of the housing. This plate has a series of suitably-staggered projections or pins 38 always engaged in perforations 39 in the housed portion of member 6, and which perforations extend across the keyway 20.

Ordinarily with the member 6 retracted to 95 its outermost limits the plate 35 is lifted, by reason of the upraise in the slots 37, to retract the pins 38 from the keyway, and so offer no opposition to the insertion of a key. The pins, however, are not entirely withdrawn from the holes 39, with the result that any inward movement of the actuator will carry the plate 35 along too; but if the key which is inserted into the keyway, although it be of the right width and thickness, be not 105 perforated in exact correspondence with the holes 39 and the depth of the keyway the pins 38 by reason of the shape of slots 37 will be pressed down so hard on the key when 110 it is attempted to push in on the actuator that the key will bind and the lock will refuse to work.

The only way to open the lock from the outside when set to be operated by the key alone from that side is to insert the key clear 115 to the back of the keyway. Inasmuch as the pins 38 are so staggered and so numerous as to present a practically solid front to the entry of a key or other instrument not having the proper perforations, it is impossible, as 120 has been amply demonstrated in practice, to pick the lock.

The purpose of the ledges 23 24 is to shield the outer bifurcated end of the member 6 from being pushed in by a wire or some such 125 means entered through slot 30.

It is possible that various modifications in my invention may be made without departing from the principle thereof, and I do not wish to be understood as limiting myself to 130

the specific construction as herein shown and described.

Having thus described my invention, what I claim, and desire to secure by Letters Patent, is—

1. In a lock, the combination of a support, a locking-bolt, a member reciprocal to and from the bolt and having a part to engage therewith to move the bolt in one direction, said member capable of a rotative movement to enable it to be placed in position relative to the bolt to prevent the actuation of the latter.

2. In a lock, the combination of a suitable support, a slotted locking-bolt, an actuator for the bolt said actuator having a combined rotative and reciprocal movement and operating in the slot of the bolt and at right angles to said bolt to retract the latter, and means carried by the actuator and adapted to be positioned thereby relative to the bolt to prevent the actuation of the latter.

3. In a lock, the combination of a suitable support, a slotted locking-bolt, an actuator operable in said slot and having a combined rotative and reciprocal movement, said actuator having, also, a cam-surface to engage the bolt to retract the latter, and means carried by the actuator and adapted to be positioned thereby relative to the bolt to prevent the actuation of the latter.

4. In a lock, the combination of a suitable support, a locking-bolt, an actuator mounted to oscillate and also to reciprocate transversely to the movement of said bolt, means in the path of the actuator and engageable thereby to effect the reciprocation of the bolt, and means to lock the actuator against rotative movement to enable it to prevent the actuation of said bolt.

5. In a lock, the combination of a suitable support, a locking-bolt, an actuator mounted to reciprocate transversely to the movement of the bolt, means in the path of the actuator and engageable thereby to effect the reciprocation of the bolt, said actuator capable of a rotative movement to enable it to be placed in position relative to the bolt to prevent the actuation of the latter.

50 6. In a lock, the combination of a suitable support, a locking-bolt and actuating means therefor, said means including a wedge member operating at right angles to the locking-bolt and engageable with the latter to retract the same, said member also capable of a rotative movement in a plane parallel with the bolt, and means shiftable in unison with the axial movement of the bolt to enable it to be positioned to lock the member against rotative movement and the bolt against reciprocal movement.

65 7. In a lock, the combination of a suitable support, a locking-bolt having a slotted part, means to actuate said bolt, said means including a wedge-shaped actuator reciprocal

in the slot in said bolt, means to maintain the bolt in the path of the actuator, and means to permit said actuator to be turned to prevent the operation of the bolt.

8. In a lock, the combination of a bolt, an actuator reciprocal transversely to the bolt and capable of a rotative movement, means to reciprocate said actuator to retract the bolt, means pressing the latter constantly into the path of said actuator, and means to prevent the operation of the bolt when the actuator is turned in certain positions.

70 9. In a lock, the combination of a locking-bolt, an actuator therefor and reciprocal transversely thereto, said actuator capable of rotation as well as reciprocation and having an inclined surface to engage a part of the bolt to retract the latter, means tending to carry the bolt always outward into the path of said inclined surface, key means to operate 80 the actuator, and means to permit the actuator to be operated with or without a key.

75 10. In a lock, the combination of a locking-bolt, an actuator therefor and reciprocal transversely thereto, said actuator capable of 90 rotation as well as reciprocation and having an inclined surface to engage a part of the bolt to retract the latter, means tending to carry the bolt always outward into the path of said inclined surface, key-operating means 95 for the actuator, means to permit the actuator to be operated without a key, and means to lock the actuator and bolt against movement.

11. In a lock, the combination of a locking-bolt, an actuator reciprocal transversely of the bolt to operate the latter, said actuator also adapted to have a rotative movement, a carrier for the actuator capable of a limited reciprocating movement, said carrier and actuator capable of being reciprocated in unison, and means to prevent the reciprocation of the carrier, for the purpose described.

100 12. In a lock, the combination of a locking-bolt, a hollow knob-shank or equivalent support, a carrier in said knob-shank mounted for reciprocatory movement, an actuator supported by said carrier and having a reciprocating movement independent thereof and engageable with the bolt to retract the same, 110 means to permit the carrier to be operated by hand to retract the bolt and means also to prevent the actuation of the carrier, and means to operate the actuator independently of the carrier.

115 13. In a lock, the combination of a locking-bolt, an actuator therefor reciprocal transverse thereto and having a cam-surface to engage the bolt to operate the latter, means for holding the bolt in contact with said cam-surface, a housing for the actuator, said actuator having a keyway and also having perforations intersecting said keyway, a tumbler-plate movable in suitable cam-slots or guide-ways in the housing and movable in unison 125 130

with the actuator and having a series of pins fitting the perforations in the actuator and adapted to be projected across the keyway on the proper reciprocation of the actuator, and means to reciprocate the actuator.

14. In a lock, the combination of a locking-bolt, an actuator reciprocal transverse to the bolt and having a cam-surface engageable with the bolt to operate the latter, a housing 10 in which the actuator is slidable, said actuator having an outer bifurcated end to provide a keyway, said bifurcated portions fitting above and below respective ledges in the end of the housing to prevent the insertion of any instrument behind the actuator, and means 15 to reciprocate the actuator.

15. In a lock, the combination of a locking-bolt, an actuator reciprocal transverse to the bolt and having a cam-surface engageable with the bolt to operate the latter, a housing in which the actuator is slidable, said actuator having an outer bifurcated end to provide a keyway, said bifurcated portions fitting above and below respective ledges in the end of the housing to prevent the insertion of any instrument behind the actuator, means to reciprocate the actuator, and means to permit the housing and actuator to be reciprocated in unison.

30 16. In a lock, the combination of a locking bolt, an actuator reciprocal transverse to the bolt and having a cam-surface engageable with the bolt to operate the latter, a housing in which the actuator is slidable, said actuator having an outer bifurcated end to provide a keyway, said bifurcated portions fitting above and below respective ledges in the end of the housing to prevent the insertion of any instrument behind the actuator, and

35 40 means to reciprocate the actuator, said actuator having perforations intersecting said keyway, and a tumbler-block supported in suitable guides in the housing and having pins fitting said perforations and adapted to be projected across the keyway.

45

45 be projected across the keyway.

17. In a lock, the combination of a locking-bolt, an actuator reciprocal transverse to the bolt and having a cam-surface engageable with the bolt to operate the latter, a housing

50 in which the actuator is slidable, said actuator having an outer bifurcated end to provide a keyway, said bifurcated portions fitting above and below respective ledges in the end of the housing to prevent the insertion of

55 any instrument behind the actuator, means to reciprocate the actuator, and means to set the actuator to prevent the operation of the bolt.

18. In a lock, the combination of a locking-bolt, an actuator reciprocal transverse to the bolt and having a cam-surface engageable with the bolt to operate the latter, a housing mounted for reciprocation in which the actuator is slideable, said actuator having an outer

bifurcated end to provide a keyway, said bifurcated portions fitting above and below respective ledges in the end of the housing to prevent the insertion of any instrument behind the actuator, means to reciprocate the actuator, and means to set the actuator to prevent the operation of the bolt.

19. In a lock, the combination of a latch-bolt, inner and outer knobs, an actuator reciprocal transverse to the bolt and engageable therewith to operate the bolt, a sliding support in the outer knob for one end of the actuator, the other end of the actuator connected with the inner knob, and said inner knob capable of reciprocation to allow the operation of the actuator. 80

20. In a lock, the combination of a slotted locking-bolt, an actuator extending through the slot therein and having cam-surfaces to engage therewith, means to hold the bolt in operative position relative to the cam-surfaces, means to support the actuator to permit of its reciprocation to operate the bolt, and means to permit the actuator to be turned to prevent the operation of the bolt.

21. In a lock, the combination of a slotted locking-bolt, inner and outer knobs, said outer knob being hollow and stationary, said inner knob having a reciprocating and rotative movement, an actuator connected with the inner knob passing through the slot in the bolt and having cam-surfaces to engage therewith and being supported at its outer end in the outer knob. 90 95

22. In a lock, the combination of a slotted locking-bolt, inner and outer knobs, said outer knob being hollow and stationary, said inner knob having a reciprocating and rotative movement, an actuator connected with the inner knob passing through the slot in the bolt and having cam-surfaces to engage therewith and being supported at its outer end in the outer knob, and means to regulate the operation of the actuator in the outer knob. 100 105

23. In a lock, the combination of a slotted locking-bolt, inner and outer knobs, said outer knob being hollow and stationary, said inner knob having a reciprocating and rotative movement, an actuator connected with the inner knob passing through the slot in the bolt and having cam-surfaces to engage therewith and being supported at its outer end in the outer knob, and connected with the inner knob. 110 115

24. In a lock, the combination of a slotted locking-bolt, a reciprocating actuator passing therethrough and having cam-surfaces to engage therewith and operate the bolt on the reciprocation of the actuator, said actuator mounted for rotative movement, a hollow stationary outer knob in which one end of the actuator is supported, an inner knob connected with the other end of the actuator, means by

which the actuator may be operated with or without a key from the outside, and means associated with the inner knob to set the actuator so as to permit its operation by a key alone from the outside, or without a key from the outside, or to prevent wholly its operation from the outside.

In testimony whereof I have hereunto set my hand in presence of two subscribing witnesses.

JOHN JORGENSEN.
